UNITED STATES PATENT OFFICE.

WILLIS C. SWIFT, OF COSHOCTON, OHIO.

APPARATUS FOR MAKING PIPE-MOLDS.

1,079,959.

Specification of Letters Patent.

Patented Dec. 2, 1913.

Application filed December 18, 1909. Serial No. 533,942.

To all whom it may concern:

Be it known that I, WILLIS C. SWIFT, a citizen of the United States, at present residing at Coshocton, county of Coshocton, 5 State of Ohio, have made a certain new and useful Invention in Apparatus for Making Pipe-Molds, of which the following is a specification.

This invention relates to apparatus for 10 use in making molds, and particularly sand molds employed in the manufacture of pipes.

The object of the invention is to provide 15 means which are simple and efficient for supplying automatically to the flask as the mold is made, the sand or other composition required to make the mold, and in such uniform quantities as are required to produce uniformity in the mold when completed.

A further object is to provide means whereby the mold forming operation and the supply of sand to the mold forming mechanism, may be carried on continuously 20 and uniformly.

Other objects of the invention will appear more fully hereinafter.

The invention consists substantially in the combinations, location, construction, 30 and relative arrangement of parts, all as will be more fully hereinafter set forth, as shown in the accompanying drawing, and finally pointed out in the appended claims.

In the accompanying drawing: Figure 1 is a view in central longitudinal section of a mold forming mechanism embodying the principles of my invention. Fig. 2 is a broken view in longitudinal section, showing a modified arrangement embraced 35 within the scope of my invention. Fig. 3 is a view in transverse horizontal section on the line 3, 3, Fig. 1. Fig. 4 is an end view of the lower end of the tube employed in the modified arrangement of Fig. 2. Fig.

40 5 is a broken view in longitudinal section of another modified arrangement embraced in the scope of my invention. Fig. 6 is a broken detail view in longitudinal central section showing the hinged hopper gates or doors and supporting fingers, of the construction shown in Fig. 2.

The same part is designated by the same reference sign wherever it occurs throughout the several views.

55 In the manufacture of molds, and particularly sand molds for use in cast iron

pipe making, it is of very great importance to secure molds of uniform density throughout. If a mold is formed with "soft spots," or portions thereof of different relative 60 densities, then the result is that when the pipe is cast in the mold, or when the molten metal is poured into the mold in casting the pipe, the mold is liable to break down and hence spoil the casting. And in the 65 practical operation of apparatus of this nature and the rapid and economical manufacture of pipes it is desirable to secure molds of such uniform character and density throughout by a continuous action of the 70 mold forming operation.

In the manufacture of molds as heretofore carried out it has been proposed to supply the sand or other composition to the flask in which the mold is formed by hand, 75 or by a workman suitably stationed for the purpose, the said sand or composition being supplied by the workman from time to time as the body pattern advances into the flask to form the mold. The practical difficulty 80 with this former procedure and which rendered it unsatisfactory and objectionable, is that a workman is unable to see down into the flask into which he is required to deposit the successive quantities of sand, so 85 as to determine just exactly the amount of sand required to be deposited at any given instant; and consequently the workman is liable to supply too much or too little sand at any given time. If too small an amount 90 of sand is supplied at any time a soft place is left in the mold at that point, and if too great an amount of sand is supplied to the flask, the sand is liable to pack and block the further advance of the ramming head 95 of the body pattern, thereby arresting the entire mold forming operation of the machine.

It is among the special purposes of my present invention to provide means for obviating the objections noted, and in carrying out my invention I propose to employ automatic means for regulating and controlling the supply of sand in such manner that the sand is supplied in uniform quantities as required and as the rammer and body pattern advance into the flask to perform their work, thereby insuring the production of molds of uniform density throughout, and avoiding interruption of the continuous operation of 100 the machine.

My invention may be carried out in a wide

variety of specifically different constructions. While, therefore, I have shown, and will now describe various forms of embodiment of my invention, I wish it to be understood that, 5 in its broadest scope as defined in the claims, my invention is not to be limited or restricted to the particular constructions shown and described.

So far as my present invention is concerned the particular construction of mold forming mechanism employed in connection with my invention in the details thereof is not of material consequence. As an operative arrangement which I have selected for 10 the purpose of illustrating the application of my invention to practical use, I have shown a plunger B, operating in a cylinder A, by hydraulic pressure, the water being admitted to the lower end of the cylinder 15 through a pipe connection H, and being exhausted therefrom through connection O, controlled by a valve X, operated and controlled by a rod I. The plunger B, carries a body pattern D, designed to advance into 20 a flask F, positioned in line with the line of movement of the pattern D, and to properly iron out or smooth the interior surface of the mold. At its end the body pattern terminates in a ramming head E, designed 25 to compress the sand in the flask, and to shape the same properly to form the body of the mold. The body pattern D operates through a socket pattern V, positioned at the base of the flask, and which is designed 30 to be engaged by some convenient part of the plunger or body pattern, as the latter approach the final limit of their advancing movement into the flask, and thereby moved toward the base end of the flask in order to 35 compress the sand at the socket end of the mold, and shape and form the same. The flask and socket pattern are supported in proper alignment with the plunger and body pattern. A supporting plate M, is shown 40 for this purpose, this plate being carried by supporting standards G. The flask, which is removable may be secured and locked in its centered and aligned position as, for instance, by dowel pins and cotters, as indicated at 45 50 C, or otherwise as may be desired.

In the operation of an apparatus such as above described after the flask and socket pattern have been properly positioned and centered, the body pattern is moved into the 55 flask through the socket pattern until the ramming head extends entirely through the socket pattern, as shown in Fig. 1. Sand is then shoveled by a workman into the upper end of the flask in sufficient quantity to just 60 cover the ramming head of the body pattern. This pattern is then still farther advanced into the flask, and additional quantities of sand are added from time to time to keep the advancing end or rammer head of the 65 body pattern covered. The very great diffi-

culty heretofore experienced in the use of apparatus of this nature is that it is impossible to know or to ascertain whether the exact amount of sand required at any time has been supplied. It is impossible for the 70 workman to see down into the flask, and as the supply of the sand is necessarily more or less intermittent the result is that soft places due to too little sand, occur at points throughout the length of the mold, or else a 75 choking or locking effect is produced by too great a supply of sand, thereby necessitating an arrest of the operation. The occurrence of either of these difficulties is exceedingly 80 objectionable.

In accordance with my invention I avoid the difficulty by supplying the sand to the flask automatically as the body pattern advances into the flask, and in just the required amounts to prevent the formation of soft 85 parts or to cause choking or clogging of the operation.

In Fig. 1 I have shown one arrangement for carrying my invention into practical use, and as applied to the mold forming 90 mechanism above described. In this arrangement I employ a hopper 10 which in the form shown, but to which my invention as defined in the claims is not to be limited or restricted, is rectangular in cross section, 95 and open at its lower end. This hopper rests upon or is carried or supported by an open ended sand chute 11, the latter in turn, when the apparatus is in position for use, resting upon or being supported by the open 100 end of the flask, and delivering into the flask. A series of plates or trays, 12, are arranged within the hopper 10, and spaced at equal distances apart therein. These plates or trays are connected by hinges, as 105 indicated at 13, to one side of the hopper whereby they may swing thereon. They are retained in horizontal position in transverse relation with respect to the hopper 10, by means of latches 17 yieldingly held in 110 engaging relation by means of springs 15, see Fig. 3. When these plates or trays are held in position by their retaining spring latches, they divide the hopper into a series 115 of chambers or pockets of equal volume. Now by filling all of these chambers or pockets with sand and then successively releasing the spring retaining latches of the trays or plates, as the body pattern and its ramming head advance into the flask, the successive small chambers or pockets deposit their respective charges of sand into the flask. A convenient arrangement for successively releasing the trays or plates, commencing with the lowermost one, is shown 120 wherein a rod 16, is provided and is mounted on the end of the ramming head E. This rod is provided with a beveled upper end, which is arranged to slide under the successive latches 17, and force them out of re- 125 130

taining relation with respect to the plates or trays, thereby successively releasing the plates or trays 12, as the body pattern and rammer head advance through the flask. 5 The distance apart of the plates or trays to provide the required area of chamber for the correct amount of sand to be deposited each time into the flask can be readily determined by experiment, and, when once 10 determined remains fixed. The rod 16, by means of which the retaining devices of the plates or trays are released, may be guided in its advancing movement in any suitable manner. For instance, it may operate 15 through a slot or opening in the sand chute 11, or the spring latches themselves may constitute guides for said rod. The operation of this arrangement is very simple. With the parts in position ready for the operation to begin the body pattern and its 20 ramming head are advanced into the flask, thereby also advancing the rod 16, and releasing the retaining device of the first shelf or tray 12, and hence permitting its charge 25 of sand to spill down the chute 11 and into the flask. The further advances of the body pattern, its ramming head and the rod 16, successively release the several trays which thereupon deposit their charges of 30 sand, in like manner, into the flask. In this manner the automatic supply of the required amounts of sand is secured, and the operation is carried on continuously without danger of forming soft places in the mold or 35 of clogging up. After the last plate or tray required to be released has spilled its charge into the flask the ramming head is advanced through the upper end of the flask in order to ram the loose sand at that end. The body 40 pattern is then withdrawn from the flask, the rod 16, hopper 10 and chute 11, are removed, by means of a crane or otherwise, and the flask, with the mold formed therein, is then removed and replaced by an empty 45 flask, a filled hopper together with its chute and a releasing rod 16, are then placed in position and the apparatus is again ready for the next operation.

The hoppers may be filled in any suitable manner. I have shown an arrangement wherein the hopper is placed horizontally with the upper side thereof open, and a sand riddle, indicated at 18, is located above the upper open side of the hopper 50 for the purpose of flaking the sand into the compartments formed in the hopper by the plates or trays 12. When these compartments are thus filled, the open side of the hopper is closed and the hopper is ready 55 to be applied to the flask on the molding machine.

The sand chute 11, is not an essential of my invention and can be omitted, as indicated, in Fig. 5, wherein the hopper is 60 shown as made in two parts 19, 20, each

provided with compartments formed by hinged trays or plates 12. In this arrangement the spring locking latches for the plates are positioned on the opposed faces of the hopper parts 19, 20, to be released by the rod 21, which, for this purpose has its releasing end provided with a double bevel, as shown.

In Figs. 2 and 4 I have shown a modified arrangement embraced within the spirit and scope of my invention, wherein a cylindrical or tubular hopper 22 of desired length is designed to fit loosely into the flask. Supporting legs 23 secured to the lower end of the tubular hopper extend below said lower end and rest upon the rammer head E, thereby forming a support for the hopper. At its lower end the hopper is provided with a door made in sections 24, hinged to the hopper by hinges 26, and controlled by a chain or other suitable connection, 25 extending up through the hopper and having short sections at its lower end respectively connected to the door sections 24. By slackening this chain or connection the door sections swing downwardly under the weight of the sand imposed thereon to cause the sand with which the hopper is filled to spill out through the lower end of the hopper into the flask and over and around the upper end of the ramming head of the body pattern. This spill of the sand continues as the ramming head advances. The space required to be filled by this spilling sand is, of course controlled by the height above the ramming head at which the lower end of the hopper is supported. This height is regulated by the length of the supporting legs 23, and when this height is once determined by experiment to suit the particular requirements of the case, it remains fixed at that point.

Other specific forms of apparatus may be devised and employed for carrying my invention into operation and still fall within the spirit and scope of my invention as broadly defined in the claims.

Having now set forth the object and nature of my invention and various constructions and arrangements embodying the principles thereof, what I claim as new and useful, and of my own invention, and desire to secure by Letters Patent, is:—

1. The combination with a flask, a body pattern, and means for operating the latter, of a hopper supported on the flask and delivering thereto, a series of plates or trays arranged in the hopper to divide the same into compartments, each compartment adapted to contain sand, retaining devices for said plates or trays, and means for automatically releasing said retaining devices in succession.

2. The combination with a flask, a body pattern, and means for operating the lat-

- ter, of a hopper supported on the flask and delivering thereto, a series of plates or trays arranged in the hopper to divide the same into compartments, each adapted to contain sand, retaining devices for said plates or trays, and means operated by the advance of the pattern into the flask for successively releasing said retaining devices.
- 10 3. In an apparatus for making sand molds, a pattern, a flask open at both ends and arranged in line with the pattern, means for advancing the pattern into the flask through one end thereof, and means controlled by the pattern as it advances into the flask for automatically supplying sand to the flask through the other end thereof.
4. In an apparatus for making sand molds, a pattern, a flask open at both ends and arranged in line with the pattern, means for continuously advancing the pattern into the flask through one end thereof, and means controlled by the pattern for automatically supplying sand to the flask through the other end of the flask as the pattern advances into the flask.
5. In an apparatus for making sand molds, a pattern, a flask open at both ends and arranged in line with the pattern, a sand hopper arranged to deliver sand into one end of the flask, means for advancing the pattern into the flask through the other end thereof, and means operated by the pat-

tern as it advances into the flask to control the delivery of the sand from the hopper into the flask.

6. In an apparatus for making sand molds, a pattern, a flask open at both ends and arranged in line with the pattern, a sand hopper arranged above the upper end of the flask, means for advancing the pattern into the flask through the lower end of the flask, and means operated by the pattern as it advances into the flask for controlling the delivery of successive quantities of sand from the hopper into the flask.

7. In an apparatus for making sand molds, a pattern, a flask open at both ends and arranged in line with the pattern, a sand hopper having a series of compartments adapted to contain the molding sand and arranged over the upper end of the flask, means for advancing the pattern into the flask through the lower end of the flask, and means operated by the pattern as it advances into the flask for successively opening said compartments to cause the sand contained therein to be delivered into the flask as the pattern advances.

In testimony whereof I have hereunto set my hand in the presence of the subscribing witnesses, on this 14 day of Dec. A. D., 1909.
